FIG. 6.

INVENTOR
Frank Barravecchia,
By Noratio E. Bellows,
ATTORNEY

UNITED STATES PATENT OFFICE.

FRANK BARRAVECCHIA, OF WESTERLY, RHODE ISLAND.

CHIMNEY FIRE-EXTINGUISHER OR FLUSHER.

1,373,160.

Specification of Letters Patent. Patented Mar. 29, 1921.

Application filed April 20, 1920. Serial No. 375,290.

To all whom it may concern:

Be it known that I, FRANK BARRAVECCHIA, a subject of the King of Italy, residing at Westerly, in the county of Washington and 5 State of Rhode Island, have invented certain new and useful Improvements in Chimney Fire-Extinguishers or Flushers, of which the following is a specification.

My invention relates to devices for flushing and extinguishing fires in chimneys.

The essential objects of my invention are to provide such means; to prevent start or headway of chimney fires whereby the adjacent and inflammable portions of the building would be endangered; to remove any 15 accumulation of soot without the necessity of using a swab; to provide an adequate sprinkling member; and to attain these ends in an inexpensive and durable structure comprising a minimum number of parts.

To the above ends essentially my invention consists of such parts and in such combinations of parts as fall within the scope of the appended claim.

25 In the accompanying drawings which form a part of this specification—

Figure 1 is a transverse section of a chimney and the adjacent portions of a dwelling house, showing my device in side elevation,

30 Figs. 2 and 3, plan and side elevations respectively of the spraying head,

Fig. 4, a section of the head and adjacent pipe portion on line 4—4 of Fig. 2,

Fig. 5, a plan view of the dispersing member of the head, and

Fig. 6, a section of the head on lines 6—6 of Fig. 2.

Like reference characters indicate like parts throughout the views.

40 In the drawings 8 is the flue of a chimney 9 passing through the roof 10, and floors 11, 12, and 13 of a dwelling, and resting upon a foundation 14. In the chimney wall are the usual thimbles 16, 17, and 18. Mounted in 45 the chimney is a vertical discharge pipe 20 supported by horizontal inlet pipes 21, 22, and 23 passing through openings 24, 25, and 26 respectively in the chimney wall, successively above the second floor 12, first floor 13, 50 and below the latter. The inlet pipes are joined to the discharge pipe by the pipe unions 28, 29, and 30 respectively, and are provided respectively with hand operated valves 31, 32, and 33. On the lowest inlet 55 pipe 23 is a depending branch pipe 35 pro-

vided with a drain valve 36. The inlet pipes extend from any usual convenient source of water supply. The inlet pipes conduct the water from the water main to the discharge pipe 20 under pressure and 60 the valves upon the inlet pipes when manually turned admit or cut off the supply to the discharge pipe. By this means my device is out of operation except when an emergency occurs in which case it is possible to immediately put the device into 65 operation by turning one or more of the valves. The location of the inlet pipes being adjacent and above each floor of the entire building makes it possible for a person standing upon the floor to operate the 70 valve. The arrangement upon all the floors of the house in every story makes it possible for the householder to set the device in operation from whatever floor he happens to 75 be when the fire is discovered. This is extremely important also in cases where the fire may have cut off the operator from access to one supply pipe, but not all.

The upper portion of the discharge or 80 stand pipe has an inwardly and downwardly directed neck portion 37 provided with a thread 38 adapted to engage a discharging head.

The head comprises an octagonal shank 40 85 provided with an axial bore or hole 41 having a thread 42 engaging the thread 38. Integral with the neck or shank portion 40 is a rectangular base portion 44 provided with a pyramidal flaring bore 45. A guide 90 plate is provided having a body 47 of rectangular contour to correspond to the periphery of the portion 44, and a pyramidal upper face 48. Integral with its corners are spacing lugs 49. The latter abut against the 95 member 44. The members 44 and 47 have at their corners plane and threaded openings 50 and 51 respectively to receive screws 53. There is formed by the spaced faces 48 of the plate 47 and the pyramidal faces of the 100 bore 45 a quadrilateral, inwardly and downwardly disposed water way 54 which discharges the water laterally in sheets rather than as a spray. Inadequate results have been obtained in my experiments by the use 105 of discharging devices wherefrom the water emerged as a spray, or where the device discharged as a sprinkler through perforations.

In operation, upon the discovery of a fire a person will operate the valve nearest at 110

hand to admit the water. For flushing purposes the basement valve 33 is opened preferably to the others.

I claim:—

- 5 In a chimney flushing and fire extinguishing device, the combination of a building having floors, a chimney traversing this building, a vertically disposed discharge pipe mounted in the chimney, an arched
- 10 neck upon the pipe near the top of the chim-

ney, a depending discharge head upon the end of the neck, distributing pipes upon the discharge pipe extending through the chimney and above the floors, and valves in the distributing pipes in the portions above the 15 floors.

In testimony whereof I have affixed my signature.

FRANK BARRAVECCHIA.
